UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,405,441.

Specification of Letters Patent. Patented Feb. 7, 1922.

Application filed July 16, 1921. Serial No. 435,156.

To all whom it may concern:

Be it known that I, ALONZO E. RHOADES, a citizen of the United States, residing at Hopedale, in the county of Worcester and 5 State of Massachusetts, have invented an Improvement in Warp Stop Motions for Looms, of which the following description, in connection with the accompanying drawings, is a specification, like characters on the 10 drawings representing like parts.

This invention relates to warp stop motions for looms whereby the loom is brought to rest when a warp thread becomes broken or too slack.

One of the objects of the present invention is to provide a warp stop motion which shall be simple in construction and efficient in 15 operation, and wherein the parts are so combined that no injurious effect is produced 20 upon the warp detectors or drop wires when a warp fault occurs and loom stoppage is effected. The present invention is a further development and improvement on the warp stop motion which forms the subject-matter 25 of the patent of Alonzo E. Rhoades, Number 1,385,711, dated July 26, 1921.

In the drawings:

Figure 1 is a perspective view of portions 30 of a loom having the present invention associated therewith, some of the parts being broken away;

Fig. 2 is a sectional side elevation showing some of the parts in section and in the position they occupy on the back or inactive 35 stroke of the actuator;

Fig. 3 is a side sectional elevation transversely of the loom showing the present invention associated therewith and the stop motion being operated to effect loom stop- 40 page;

Fig. 4 is a longitudinal section through the connection between the movable toothed bar and arm of the rocker;

Fig. 5 is an enlarged face view of the 45 guide for the stop arm and associated parts; and

Fig. 6 is an enlarged sectional elevation of the knock-off mechanism in the act of being 50 operated by the backward movement of the lay.

The present invention has special reference to that type of warp stop motion where- in a normally fixed and movable toothed bar cooperates with the warp detectors or drop

wires to effect loom stoppage when one of 55 the warp detectors or drop wires is released by a warp thread. The movable toothed bar (of which there may be one or more, as occasion may demand) is connected to an actuator through a rocker which moves with 60 and is adapted to rock upon the actuator, but is normally held from rocking movement by means such as a weight so long as the warp threads are in normal condition. Connected to the rocker is a latch which normally moves in a path of nonengagement 65 with a stop arm so long as the warp threads are intact, but which, when a warp thread becomes broken or too slack, is moved by the rocker to engage and effect movement of 70 the stop arm to effect loom stoppage.

It is sometimes desirable in a loom having a warp stop motion, to provide the lower or cam shaft with a number of trains of mechanism for shedding the warp, and under such conditions, the operation of the actuator from the under or cam shaft is undesirable, and one of the features of the 75 present invention as an improvement over the construction of the prior patent, consists in operating the actuator from the crank-shaft so that the train of mechanism for operating the actuator is removed from interfering relation with the shedding mechanism.

The loom frame 1 is supplied with supporting means for sustaining the toothed bars and some of the associated parts, and such supporting means, as shown in the present invention, may be conveniently provided by brackets 2, one at each side of the loom, to which may be adjustably secured the bar-supporting brackets 3. In the present instance the brackets 3 are provided with outwardly-extending lug portions 4 95 provided with slots 5 through which passes the bolt 6 for adjustably connecting the bracket 3 with the brackets 2. This construction provides a convenient means for attaching the bar-supporting brackets 3 to 100 the side frames of the loom, but it is to be understood that the invention is not restricted to this particular means.

Extending between the brackets 3, one at each side of the loom, are the warp-supporting bars 7, over which pass the warp threads 7 a. Any number of the supporting bars 7 suitable to the intended purpose may be em- 105

ployed, only one of such bars being shown as they are well understood features of a warp stop motion.

The brackets 3 are provided with the 5 standing lug portions 8, to which are secured the fixed toothed bars 9, two of such bars being shown, Fig. 1. Each of the fixed toothed bars 9 may comprise two members, although one may be sufficient in some instances, and such bars are provided with teeth. Between the two members of the toothed bar 9 is a movable toothed bar 10, also provided with teeth, and in the present instance facing in the opposite direction 15 from the teeth on the fixed bars 9. The fixed bars 9 may be secured in lugs 8 of the brackets 3 by means of wing nuts 11 or other suitable securing means.

Mounted in suitable bearings 12 carried 20 by the loom sides is the crank-shaft 13 having the usual pitman 14 connected thereto, and secured upon the crank-shaft is the toothed wheel which, as shown, is conveniently formed as a worm 15, the teeth of 25 which are in operative engagement with the teeth of a worm-wheel 16 suitably supported on the bracket 17 projecting from one side of the loom, the construction being such that the worm and worm-wheel 30 driven from the crank-shaft enables the actuator-operating means to be placed in non-interfering relation with the bottom or cam shaft 18.

Pivottally supported at 19 preferably near 35 the lower portion of the loom frame, is the actuator 20 which, in the present instance of the invention is contrived as an arm extending upwardly from its support 19 and connected at 21 with a link 22, the other 40 end of which is connected at 23 with a pin eccentric with respect to the worm-wheel 16. The pin 23 may be conveniently secured to the face of the worm-wheel, the construction being such that as the worm-wheel 16 is rotated through the gearing connection 45 with the crank-shaft, the actuator will be given its detecting movements. In order that the actuator may be positioned sufficiently rearward of the crank-shaft to prevent interference therewith, the actuator 20 is provided with an extension 24 which is connected to the link 22 at 21. Thus the 50 gearing connecting the worm and worm-wheel as described, to the crank-shaft, may be effected without interference with the shedding mechanism or other operating parts, and yet the actuator may be properly related with the crank-shaft and parts of the warp stop motion.

60 Mounted upon the actuator 20 is the rocker 25 which is bodily movable with and adapted to rock upon the actuator. In the present instance the rocker is mounted upon the actuator 20 by means of a pin 26 and has one arm 27 connected to the movable

toothed bar (one or more, hereinbefore described) and another arm 28 which carries a latch 29.

In the present form of the invention, where one of the toothed bars is fixed and the other is movable, injury to the warp detectors or drop wires is liable to occur when a drop wire is released by a warp thread and locks the movable bar to the fixed bar. To avoid this undesirable condition, the rocker arm 27 is connected to the movable toothed bar or bars 10 by a yielding member 29. In the present instance the member 29 comprises a head portion 30 having a stem 31 which extends longitudinally through a casing 32. The stem 31 has an adjustable head 33 secured thereto within the casing 32, and between the head 33 and the end of the casing is a spring 34. The casing 32 has side projecting lugs or pins 35 which engage the slotted end portions of the movable toothed bars 10, two in the present instance, and the head 30 of the stem 31 is pivotally connected to the arm 27 as at 36, the construction being such that should a movable toothed bar 10 be arrested in its movement with the actuator by a warp detector or drop wire which has been released by a slack or broken warp thread, the spring 34 may yield sufficiently to prevent injurious effect upon the warp detector.

The latch 29 hereinbefore described, is adjustably mounted upon the arm 28 of the rocker and secured in adjusted position by a bolt 37. The latch 29 may constitute not 100 only a latch, but also a weight which may normally act upon the rocker to hold the arm 27 of the rocker against a stop 38 forming part of or secured to the upper end portion of the actuator 20.

The latch 29 may be variously formed, but in the present instance it is shown as provided with a slot 39 through which extends a stop arm 40 having a projection or lug 41 which may constitute a catch adapted to 110 be engaged at times by the latch to effect movement of the stop arm when the rocker is rocked upon the actuator by a drop wire or detector.

The stop arm 40 is mounted in the present instance for longitudinal movement by the latch 29 when the rocker is turned upon the actuator, and such longitudinal movement of the stop arm is utilized to effect loom stoppage. The stop arm 40 is mounted 120 in a guide 42 which is provided with a slot 43 through which the stop arm extends. The opening in the guide 42 is enlarged at 44 to permit the stop arm to move not only longitudinally therein, but also to tilt to some 125 extent under the action of the latch (see Fig. 5).

Mounted upon the bracket 42 is a tube 45 through which extends the wire 46 which is encased or surrounded by an armor 47 of 130

such size relative to the wire 46 as to permit the wire to move endwise in the armor 47, but prevent buckling when it is moved longitudinally therein under an endwise pressure. The stop arm has an end portion 48 which, when the stop arm is moved by the latch, engages the end of the wire 46 and moves it longitudinally in the armor or casting 47. The tube 45 may be conveniently 5 secured in the bracket 42 by a bolt 49. As a convenient mechanical construction, the tube 45 may be mounted in a block 50 preferably formed separate from the bracket 42 and secured thereto by suitable bolts 51 as indicated in Fig. 5.

The wire 46 has its other end mounted in a bracket 52 by means of a tube 53 which may be appropriately secured in the bracket 52 by a bolt 54 and the end of the wire 46 10 adjacent the bracket 42 bears upon the end of a plunger 55, the upper end of which rests against the under side of a dog 56 pivoted at 57 on an arm 58 which is itself pivotally supported on the bracket 52 at 59. A 15 spring 60 normally acts to hold the dog 56 in its lowered or inoperative position. Mounted upon the lay 61 is a bunter 62 which is adapted to engage the dog 56 when the latter is raised into the path of the 20 bunter as the lay goes back. Connected with the arm 58 is the link 63 which is connected to the knock-off lever as more fully shown and described in the patent to Burbank, No. 1,240,666, dated September 18, 1917, the construction being such that should the dog 56 25 be raised into the path of the bunter 62 as the lay goes back, the shipper will be knocked from its holding notch and the loom will be brought to rest to enable the loom 30 attendant to piece-up the broken or remedy the slack warp thread.

The spring 60 which acts upon the dog 56 is sufficient in its action to move the wire 46 35 backwardly in its armor 47 when the stop arm is released from acting upon the opposite end of the wire. To facilitate such movement of the wire 46 and to relieve the stop arm from its bearing upon the opposite end of the wire from the position indicated 40 in Fig. 3, means is provided for insuring movement of the stop arm in the opposite direction after the loom has been stopped, and the warp fault remedied. To this end the stop arm is provided with a shoulder 64 45 which, when the latch 29 is returned to its initial position as indicated in Fig. 2 after a stopping action as indicated in Fig. 3, will engage the shoulder 64 and under the weight of the latch which turns the rocker clockwise 50 relative to the actuator in the construction shown, will move the stop arm backwardly from the position in Fig. 3 to that of Fig. 2, and thus relieve the pressure of the stop arm from against the wire 46. A 55 stop 65 on the stop arm 40 limits the back-

ward movement to inoperative position of the stop arm 40.

When the loom is running with the warp threads in normal condition, the actuator will be moved back and forth through the 70 train of mechanism described, and carry with it the rocker 25 without causing rocking movement of the rocker, and the movable toothed bar will be free for movement longitudinally. When, however, a warp 75 thread becomes broken or too slack, it will lock the fixed and movable toothed bars together and thereby cause the rocker 25 to rock upon the actuator and lift the latch 29 into engagement with the stop arm and 80 draw the stop arm longitudinally to effect lengthwise movement of the wire 46 and effect loom stoppage. When the warp fault has been remedied and the dropped warp detector has been lifted from the interlocking 85 engagement with the fixed and movable toothed bars, the weight of the latch 29 upon the arm 28 will again restore the rocker to its normal position with the arm 27 bearing against the stop 38, and on the 90 backward movement or the inactive stroke of the actuator, the latch will engage the shoulder 64 of the stop arm and move it into its normal or inoperative position, as indicated in Fig. 2.

What is claimed is:—

1. In a warp stop motion for looms, the combination of a fixed and a longitudinally movable toothed bar, a series of warp detectors which are hung upon and normally supported out of engagement with the toothed bars by the warp threads, an actuator, a rocker mounted on the actuator for movement therewith and rocking movement thereon, connections between the rocker and 100 movable toothed bar, means normally acting to hold the rocker from rocking movement and permitting such rocking movement when the movable toothed bar is held from longitudinal movement by a warp detector dropped by a slack or broken warp thread, means including a stop bar for stopping the loom when the rocker partakes of its rocking movement during movement of the actuator, and connections between the 105 rocker and stop bar for resetting the stopping means.

2. In a warp stop motion for looms, the combination of a fixed and a longitudinally movable toothed bar, a series of warp detectors which are hung upon and normally supported out of engagement with the toothed bars by the warp threads, an actuator, a rocker mounted on the actuator for movement therewith and rocking movement thereon, connections between the rocker and movable toothed bar, a stop arm having a catch, a latch carried by the rocker and normally maintained out of engagement with the catch until the movable toothed bar is arrested by 115 120 125 130

a warp detector dropped by a slack or broken warp thread, and means for stopping the loom when the stop arm is moved by the engaged catch and latch during movement of the actuator.

3. In a loom, the combination of an actuator, a rocker connected to the actuator, an endwise movable toothed bar connected to the rocker for reciprocating movement thereby as the rocker is moved by the actuator, a stop arm having a catch, a latch carried by the rocker and normally supported for movement in a path out of engagement with the catch as the rocker is bodily moved by the actuator, a series of warp detectors normally supported by the warp threads and adapted to arrest the movable toothed bar and cause the rocker to effect engagement of the catch and latch when one of the detectors is dropped by a too slack or broken warp thread, and means for stopping the loom when the stop arm is moved by the engaged catch and latch.

4. In a loom, the combination of the crank-shaft, an actuator, a rocker mounted on the actuator for bodily movement therewith and rocking movement thereon, a fixed and a movable toothed bar, connection between the rocker and movable toothed bar for reciprocating the movable bar when the rocker moves bodily with but fails to rock on the actuator, a toothed wheel on the crank shaft, a toothed actuator wheel engaged with the toothed wheel on the crank-shaft, connections between the actuator wheel and the actuator for operating the latter from the crank-shaft, a series of warp detectors adapted to be supported by the warp threads and to arrest movement of the movable toothed bar when one of the detectors is released by a warp thread.

5. In a warp stop motion for looms, the combination of the loom crank-shaft having a worm thereon, a worm-wheel engaged therewith, an actuator connected to the worm-wheel and carrying a rocker, a fixed and a movable toothed bar, connections between the movable toothed bar and the rocker for reciprocating the toothed bar, a stop arm having a catch, a latch carried by the rocker which is engaged with the catch of the stop arm and effects movement of the latter only when the rocker is rocked upon the actuator, and a series of warp detectors which are normally supported by the warp threads and adapted to arrest movement of the movable toothed bar and cause rocking movement of the rocker on the actuator when one of the detectors is released by a warp thread.

6. In a warp stop motion for looms the combination of a fixed toothed bar, a movable toothed bar, a series of warp detectors which are hung upon and normally supported in

raised position by the warp threads, an actuator, a rocker mounted on the actuator and connected to the movable toothed bar to impart thereto a detecting stroke in one direction and an idle stroke in the opposite direction, means normally acting upon the rocker to prevent rocking movement of the rocker as the actuator makes its detecting stroke and permit such rocking movement without injury to a warp detector when a warp detector is dropped by a warp thread breaking or becoming too slack, and means operated on the detecting stroke of the actuator to effect loom stoppage when the movable toothed bar is arrested by a detector.

7. In a warp stop motion for looms, the combination of a fixed toothed bar, a movable toothed bar, a series of warp detectors which are hung upon and normally supported in raised position by the warp threads, an actuator, a rocker mounted on the actuator and connected to the movable toothed bar, a latch carried by the rocker, a stop arm which is adapted to be engaged and moved by the latch when the rocker is rocked on the actuator by obstruction to movement of the connected toothed bar due to a warp detector released by a broken or abnormally slack warp thread, and means for stopping the loom when the stop arm is moved by the latch.

8. In a warp stop motion for looms, the combination of a fixed toothed bar, a movable toothed bar, a series of warp detectors which are hung upon and normally supported in raised position by the warp threads, an actuator, a rocker mounted on the actuator and connected to the movable toothed bar, an arm carried by the rocker and having a latch, a stop arm normally out of the path of movement of the latch until the rocker is rocked on the actuator and then acting to effect movement of the stop arm, and means for stopping the loom when turning movement of the rocker causes the latch to engage and move the stop arm.

9. In a warp stop motion for looms, the combination of a fixed toothed bar, a movable toothed bar, a series of warp detectors which are hung upon and normally supported in raised position by the warp threads, an actuator, a rocker mounted on the actuator and connected to the movable toothed bar, a longitudinally movable stop arm, a guide for the stop arm, an arm extending from the rocker, a latch carried by the arm for normal movement in a path of non-engagement with the stop arm, and means operated by the stop arm to effect loom stoppage when the latch engages and moves the stop arm.

10. In a warp stop motion for looms, the combination of a fixed and a movable toothed bar, a series of warp detectors which are

hung upon the warp threads and normally supported in raised position, an actuator, a rocker mounted on the actuator and having two arms, one connected to the movable toothed bar and the other carrying a latch, 5 a stop arm adapted to be engaged and moved by the latch when the rocker is rocked upon

the actuator by a wrap detector released by a warp thread, and means to stop the loom when the stop arm is moved by the latch. 10

In testimony whereof, I have signed my name to this specification.

ALONZO E. RHOADES.
